UNITED STATES PATENT OFFICE

HARRY BERLIN, OF BROOKLYN, NEW YORK

BRAIDED WAVED BRAID

Application filed March 19, 1930. Serial No. 437,079.

My invention relates to braids and refers more particularly to a braid wherein the weave is alternately upset to produce a wave like effect.

5 One object of my invention is to provide a braid wherein the threads are alternately upset out of alignment with each other.

Another object of my invention is to provide a braid that has a wave like effect in 10 appearance.

A further object of my invention is to provide a braid that is alternately upset from the edges to the central portion so as to produce a wave like effect in the material.

15 A still further object of my invention is to provide a braid first made up of a straight warp and a diagonal woof and then upsetting the warp alternately toward the edges so that when thus upset the warp will 20 give a wave like effect.

It is well known in the art that braids of different kinds have been produced but none of them have ever been made that produce the effect of this unique arrangement of the 25 weave.

I attain these objects by the means illustrated in the accompanying drawings, wherein similar numerals refer to like parts throughout the several views, in which:—

30 Figure 1 is a plan of the weave before upsetting using the woof threads only.

Figure 2 is a plan of the weave after upsetting, using the woof threads only.

35 Figure 3 is a plan of the weave before upsetting using a warp and woof.

Figure 4 is a plan of the weave after upsetting using a warp and woof.

The weave shown in Figures 1 and 2 is 40 diagonal and made up of the cross threads or woof only, but it is obvious that other cross weaves could be used to produce a similar effect.

This braid is first woven as shown in Figure 1 wherein the threads 1 and 2 cross each 45 other diagonally.

Then this braid is placed in a special machine having means which alternately forces some of the threads to one side. That is, when pressure is brought at 3, 5, 7, 9 and 50 11, some of the threads will be pushed out

at 4, 6, 8, 10 and 12, as shown in Figure 2 and when thus alternately pushed out there will be formed at 13 a wave like arrangement of threads substantially in the center of the braid as clearly seen in Figure 2, where- 55 in the angular spacing of the weave indicates the displacement of the threads.

It is obvious that many variations of this offsetting method may be used and various 60 unique effects produced.

The weave shown in Figures 3 and 4 is made up of the diagonal or cross threads like 14 and 15, constituting the woof and the longitudinal threads 16 constituting the warp. 65

When the warp is alternately upset or pushed out toward the edge or alternately out of alignment in a similar manner as hereinbefore mentioned as at 17, 18, 19, 20 and 21, the result as clearly shown in Figure 70 4, will give a wave like effect.

Having thus illustrated and described the preferred embodiment of my invention, I do not wish to limit myself to the exact construction or arrangement of parts shown, 75 since it is evident that modifications may be made therein, without departing from the spirit of the invention or scope of the claims.

I claim:—

1. A new article of manufacture comprising a braid of diagonal weave wherein the threads of the longitudinal central portion are alternately forced towards the outer edge of the braid, providing a wave-like 85 zone in the center of the braid.

2. A new article of manufacture comprising a braid of diagonal weave with a longitudinally running warp wherein the threads of the longitudinal central portion are alternately forced towards the outer edge of the braid, providing a wave-like zone in the center of the braid. 90

Signed at New York, county of New York, State of New York, this 18th day of March, 95 1930.

HARRY BERLIN.
